UNITED STATES PATENT OFFICE.

ALLEN OLIVER, OF FOREST HILL, CALIFORNIA.

AMALGAMATOR AND CONCENTRATOR.

SPECIFICATION forming part of Letters Patent No. 252,793, dated January 24, 1882.

Application filed June 27, 1881. (No model.)

To all whom it may concern:

Be it known that I, ALLEN OLIVER, of Forest Hill, county of Placer, State of California, have invented an Improved Amalgamator and Concentrator; and I hereby declare the following to be a full, clear, and exact description thereof.

My invention relates to an apparatus for amalgamating and concentrating the valuable metals, and also for concentrating sulphurets; and I call it the "automatic hydraulic amalgamator and concentrator."

It consists of two sluices placed side by side, and provided with gates which are operated automatically by suspended water-boxes. A main sluice brings the pulp from the battery to these two sluices, and while one is receiving the pulp the gate of the other is closed. The sluices have a double bottom, the upper one being perforated and provided with upwardly-projecting brushes. A frame of water-pipes with transverse wedge-shaped hollow riffles, which are perforated for the egress of water into the pulp, is moved up and down continuously to agitate the pulp and assist in concentrating. Suitable discharge-gates are opened and closed automatically, and a flexible riffle at the outlet is operated in the same manner, all of which will be more fully explained by reference to the accompanying drawings, in which—

Figure 1 is a perspective view of my invention. Fig. 2 is a longitudinal section. Figs. 3 and 4 are transverse sections. Fig. 5 is a transverse section. Fig. 6 is a side view.

A is the main sluice, which brings the pulp from the batteries to my apparatus; and B are the sluices which receive the pulp and in which the concentration takes place. These sluices are preferably two in number and stand side by side, and have a sufficient angle to cause the pulp to move slowly toward the lower end, where the light portions and sand are discharged. Each of these sluices is provided with a gate, C, which serves to close it and prevent any further ingress of pulp until wanted. These gates are connected with boxes D, which move in guides above the sluices, and are suspended by a rope or chain, E. This rope passes over pulleys F, and makes a turn about a single pulley, G, being so connected with it as to turn it and its shaft, when one box rises and the other falls. Upon the shaft of this cen-

tral pulley is a gear or ratchet wheel, H, which is held at any desired point by a ratchet-bar, 55 I, and this bar is moved to release the wheel, when desired, by arms J from either of two rising and falling boxes, K, the operation of which will be described hereinafter.

A short tube, L, is fixed upon the pulley G 60 or to its shaft, so as to oscillate when the shaft is turned, and thus discharge water into either one or the other of the boxes D. This tube is supplied with water by a flexible tube from a tank, M, above the machine, which is provided 65 with a screen or filter, so that the water may be freed from sand or substances which will clog the working parts. Water is conveyed by pipes from this tank to other parts of the apparatus, as will be more fully described 70 hereinafter.

Each of the boxes D has a gate, N, at the bottom operated by a lever-arm, O, so that when the box has descended and closed the sluice-gate C, this exit-gate N will be opened 75 and the water will be discharged. The other box will be filled from the oscillating tube, so as to be ready to descend and close its gate when the ratchet-wheel is released, as before described. By this action the gates of the two 80 sluices are alternately opened and closed, and the pulp is caused to flow into one and the other, as desired.

Upon the floors or bottoms of the sluices B are fitted amalgamated plates P, and a short 85 distance above these plates are the supplemental floors or bottoms Q. These secondary bottoms have transverse depressions formed at regular intervals in their length, and these depressions are perforated, so that any gold, sulphurets, or other heavy valuable particles which settle therein will pass through into the lower compartment. Below this perforated bottom are a series of longitudinal and transverse pipes, R, which receive water from the 90 tank M, before mentioned, and these pipes are perforated, so as to discharge the water into the material below the bottom Q. This action keeps the material in constant motion upon the amalgamated plates, and at the same time, 100 by the upward flow through the holes in the perforated plates, prevents the lighter sand and the oxidized matter which prevents amalgamation from passing down into the receptacle below.

Above the perforated plates Q are a series of

plates, S, which are formed to clamp and hold the upwardly-projecting brushes T, that extend in rows across the sluices and form riffles, as shown. These brushes are formed of the filaments of what is known as "soap-root," as they do not soften or rot by the constant action of the water, and they make a valuable riffle. Spaces are left between the clamps S, so that the heavier materials may settle into the channels and perforations of the bottoms Q.

In order to keep the pulp constantly agitated in the sluices and between the brushes, I employ a moving frame, U, formed of pipes, as shown, and having the wedge-shaped hollow transverse riffles V, extending across at points between the stationary brush riffles T, and perforated so as to discharge water into the pulp. This moving hollow frame is connected with the water-tank M by a flexible pipe, and receives a supply of water therefrom. In order to move this frame and its riffles, it is provided with arms W, which curve over the sides of the sluices and are connected by pins with the united upper ends of the arms X. The lower ends of these arms diverge like the letter A, and those on one side of the angle are united with a horizontally-moving bar, Y, while those on the other side of the angle are united with another similar bar, Z. These two bars are connected by rods or pitmen with cranks a, placed diametrically opposite each other upon a shaft, b, by which they are driven, and the effect is to cause the bars Y Z to move in opposite directions, and the A-formed arms X are alternately opened and closed at the bottom, thus raising and depressing the apex, and carrying with it the hollow riffle-frame.

The transverse hollow riffles V have perforations, so as to discharge water into the pulp continuously as they move up and down, and these water-jets serve to open the material to admit the easy entrance of the riffles as they move downward and prevent its packing. As the sluices stand at an incline it will be seen that the pulp will be deeper at the lower end, and in order to keep up a perfect action throughout the whole depth I employ as many of the transverse wedge-shaped riffles as may be needed, one above another. If the sluice is long, there may be one riffle in depth for a certain distance, then two, then three, and so on for any required depth, each series above being separated from those below about the distance of the vertical travel of the frame. By this arrangement the whole mass of pulp is kept thoroughly agitated and stirred up whatever may be its depth.

The lower end of the sluices is provided with rising and falling riffles, which are gradually extended or contracted as the sluice fills or is emptied. Each riffle is constructed as follows: A hollow cylindrical case, c, extends across the sluice the full width, and has two arms, d, extending from its top to the box K, heretofore mentioned, so that the cylinder is caused to rise and fall by the movement of the

box. Within this cylinder is a smaller cylinder, e, with an axle extending through the ends of the outer cylinder. Pinions or gear-wheels f upon the ends of this axle engage with fixed rack-bars g, and when the outer case rises or falls the inner cylinder is caused to revolve by reason of the gear-wheel traveling in contact with the rack.

A flexible sheet of rubber or other suitable material, h, has one edge attached to the inner cylinder, and the other edge is fixed at the bottom or lower end of the sluice, passing out through a slot in the outer case, as shown. By this construction it will be seen that when the outer case rises the flexible rifle will be unrolled from the inner cylinder and will form a dam across the lower end of the sluice, and when the outer case is depressed the flexible sheet will be again rolled upon the inner cylinder as the case c moves downward.

In order to prevent grit or other substances from entering the case and clogging the slit through which the flexible sheet passes or from clogging the gear-wheel and rack, water is brought into the case by a flexible pipe, i, from the tank M, and this water, flowing outward through the slit, washes the flexible sheet. Holes at the end allow water to escape to keep the gears clean. The flexible riffles are raised gradually, as the pulp flows into the sluice, by means of the arms d, connected with the boxes K, as before mentioned. These boxes are floats fitted into tanks m, and these tanks are slowly filled with water by means of pipes n from the tank M, thus gradually raising the floats as fast or slow as may be desired. When the float upon one side has reached the top a suitable mechanism shuts off the supply of water, and at the same time opens a gate, by which the water is discharged from the tank, and the float will gradually sink, depressing the flexible rifle at the same time. At the same time the pulp has been shut off from that sluice by the shifting gates heretofore described, and as the flexible rifle is depressed the lighter materials and waste will flow off over the top, and the vertically-moving hollow riffles continue to rise and fall through the mass while it diminishes, thus keeping it thoroughly agitated until the separation has been completed.

Beneath the lower end of the sluice is a box, o, to receive the valuable materials when the clean up is made. The lowest floor of the sluice is perforated with a sufficient number of holes, p, to receive this material and lead it to the box, and while the sluice is filling and discharging a stream of water is led into the box, so that its pressure will prevent the light material from passing into the box. The upper grooved and perforated bottom, Q, of the sluice only extends to the edge of the box o and its perforations, and a gate, q, closes the chamber below the bottom Q until the float K has nearly reached the bottom. It then strikes a lever, which opens this gate, and the water-supply to the box o is cut off, and at the same time a dis-

charge-gate from its lower part is opened, so that all the valuable heavy materials, as they escape from the chamber or space between the floors of the sluice, will pass into the box, and 5 thence through the outlet to a point where it may be collected. The light sand and slums from this machine are discharged into a hopper with a jet of water, and the sand will settle to the bottom, while the slum will pass off 10 into another machine, which is nearly a counterpart of the one herein described; but instead of the vertically-moving frames and riffles, I employ a mat formed of soap-root fiber and stretched across a frame horizontally. 15 This mat is raised above the surface of the slum, and is then pressed down, acting like a strainer and forcing the minute particles of gold to the bottom, where it is washed off and may be amalgamated upon the plates.

20 Having thus described my invention, what I claim as new, and desire to secure by Letters Patent, is—

1. The sluices B B, connected with the main or supply sluice A, in combination with gates 25 C, rope E, and pulley G, substantially as described.

2. The boxes D, provided with the gates C, in combination with the rope E, the pulley G, and guides, substantially as set forth.

3. The sluices B, in combination with the suspended water-boxes D and automatic gates N, substantially as and for the purpose specified.

4. The boxes D, provided with the gates C, 35 and suspended as shown, in combination with the detent or ratchet wheel H, the lever I, carrying the pawl, the floats K, and tripping-arms J, all constructed, arranged, and operated as set forth.

5. The oscillating shaft carrying the pulley G and the ratchet - wheel H, in combination with the double nozzle L, secured as described, to be tilted by the movement of the shaft and discharge alternately into spouts leading to 40 the two sluices B, and the supply-tank M, substantially as described.

6. The sluices B, having the amalgamated plates P, in combination with the supplemental bottoms Q and the water-discharging pipes R, arranged beneath the supplemental bottoms Q, 50 substantially as and for the purpose herein described.

7. The sluices B, provided with the amalgamated plates and the water-pipes R, in combination with the supplemental bottoms having transverse depressions, perforated as shown, for the purpose set forth.

8. The curved transverse plates S, extending across the sluices and having their edges turned at right angles to clamp the brushes T, 60 substantially as and for the purpose described.

9. The sluice B, in combination with the upwardly - projecting soap - root brushes T, arranged transverse the sluice, as set forth.

10. The sluices B, the water-pipes U, and the wedge-shaped perforated tubes V, arranged transverse the sluice, in combination with the series of reciprocating levers W, X, X', and Z, to give the water-pipes a rising and falling motion, substantially as described.

11. The flexible riffle h, rolling upon the cylinder e within the case c, and extending across and fastened to the bottom of the sluice, in combination with the sluice B, for the purpose set forth.

12. The tanks m, having floats K, and tank M, in combination with the arms d and cases c, said arms connecting the floats to the cases, and sluices B, all constructed, arranged, and operated as described.

13. The case c, contained cylinder e, provided with pinions f, and flexible riffle h, in combination with the vertical racks g, the whole constructed, arranged, and operated as set forth.

In witness whereof I have hereunto set my hand.

ALLEN OLIVER.
